UNITED STATES PATENT OFFICE.

RICHARD JAMES PRETTIE, OF JAMAICA, NEW YORK, ASSIGNOR TO THE AEOLIAN COMPANY, A CORPORATION OF CONNECTICUT.

AUTOMATIC STOP FOR PHONOGRAHS.

1,382,544.

Specification of Letters Patent. Patented June 21, 1921.

Application filed March 24, 1915. Serial No. 16,673.

To all whom it may concern:

Be it known that I, RICHARD JAMES PRETTIE, a citizen of the United States, residing at Jamaica, in the county of Queens and 5 State of New York, have invented certain new and useful Improvements in Automatic Stops for Phonographs, of which the following is a specification.

My present invention relates to an automatic stop for phonographs and the like, the advantages of which will be apparent to those skilled in the art from an understanding of the following description in connection with the drawings.

15 In the latter, Figure 1 is a plan view of the top of a phonograph embodying my stop, the record and turntable being partly broken away to show the mechanism of the stop; Fig. 2 is a similar view except that the 20 parts are shown in tripped position resulting in throwing on the brake, whereas Fig. 1 shows the parts in set position with the brake off and the turntable supposed to be rotating with the sound-box being fed 25 across the face of the record. The remaining figures are enlarged detail views,—said Figs. 3, 4, 5 and 6 being vertical sectional views partly in elevation respectively on the section lines 3—3, 4—4, 5—5 and 6—6 30 in Fig. 2 looking in the direction of the arrows.

I will now describe the specific devices shown in the drawings. The phonograph illustrated happens to be of the usual underneath horn type with the horn concealed in the cabinet 1. 2 is the tone-arm pivotally supported in the top shelf 3 of the cabinet and carries the reproducer 4 which as usual may be fed across the face of the record by 40 the contact of the stylus with the spiral groove in the record 5, supported on turntable 6, the latter in turn being supported on and rotated by the motor-spindle 7.

The particular illustrated embodiment of 45 my stop mechanism is substantially concealed under the turntable and is supported on cabinet-shelf 3. It comprises brake-means, a brake-latch, brake-setting means, and brake-latch releasing means adjustable 50 to be operated at any point of play from the record, all shown self-contained in the sense that they are mounted on one and the same base-plate 8 secured by screws 9 to the shelf. It further comprises independent 55 means which operates the above from the

travel of the sound-box, said means consisting of an arm 10 secured to the vertical neck of the tone-arm (Figs. 1 and 5), the link 11, and the operating finger 12 pivoted at 13 to a supporting foot 14, which latter is 60 screwed to the shelf 3. The result is that a swing of the tone-arm in either direction produces a magnified swing in the opposite direction of the free end of the finger 12.

Describing now in detail the other referred to, self-contained part of the stop, this comprises a brake-shoe 15 to engage the rim of the turntable supported on a horizontal outward extension 16 from one end of a horizontally disposed bell-crank 17 pivoted 70 at 18 to the base-plate 8 and having at its other end a beveled latch-engaging projection 19.

20 is a latch pivoted at 21 to the base-plate 8 and having a beveled latch-projection 22 adapted to interlock, as shown in Fig. 1, with the projection 19 on the brake-lever 17 to hold the brake-shoe in its off or non-braking position. The latch 20 extends generally parallel with the middle 80 portion of the brake-lever and there is a tension spiral spring 23 which connects the pivotal end of the latch with the shoe-end of the brake lever. The result is that the spring 23 does the double duty of pulling on 85 the shoe to brake further rotation of the turntable as soon as the brake-lever is released from the latch 20 as shown in Fig. 2; and vice versa of pulling said latch into its latching position shown in Fig. 1 when the 90 finger 12 pushes the shoe outwardly out of contact with the rim of the turntable by brake-setting means as follows:

This consists of a long, endwise movable member 24 having one end pivotally connected at 25 to the shoe-end of the brake-lever. The opposite end of this member is bent upwardly to form the upstanding projection 26 (compare Figs. 1 and 4). 27 is a link-connection between said member 24 and the base-plate 8. From Fig. 1 it will be seen that the arrangement is such that the upstanding projection 26 is in the path of the extremity of the finger 12, so that if reproducer and tone-arm be carried to the 105 right in Fig. 2, as a matter of fact to a position where the reproducer is off the record, the finger 12 will strike against said projection 26 and will push the member 24 endwise, and thereby swing the brake-lever 110

17 about its pivot 18 until it is latched back in its non-braking position shown in Fig. 1 and will so remain, with the turntable rotating, until the latch 20 is released by 5 means next to be described.

28 is a piece of round-wire (Figs. 1 and 3) having one end bent to form an upward projection 29. This member 28 is slidable endwise through a hole in a stationary lug 30 on the base-plate 8. 31 is a collar on the member 28 between which and the lug 30 is a compression spring 32 which gives the member a normal tendency to move endwise toward the latch 20. The latch-end 10 of the member 28 made of round-wire as aforesaid, is flattened to give a flat bottom 33 (Fig. 3) thereto which rests slidably on top of the latch 20 and incidentally prevents the wire 28 from rotating in the described hole in the lug 30 and so keeps the projection 29 always upright. This flattened end of the wire 28 extends through a vertically elongated eye 34 (Fig. 6) in a pin 35 supported loosely for vertical adjustment in 15 a hole through the latch 20 and a slightly larger hole through the base-plate 8. The head 35^a of the pin rests on the flattened end or toe 36^a of the finger lever 36 centrally pivoted at 37 (Fig. 3) between lugs 20 on the underside of the base-plate 8. This portion of the finger lever and related parts is located in a hole or recess in the shelf 3 (Fig. 3), whence the finger-end of the lever 36 projects and is provided with the button 38. 39 is a leaf-spring at one end 39^a secured to the latch 20 and at the other end being arranged to bear down on the pin 35 so that the member 28 is normally frictionally gripped and held stationarily between the 25 top of the eye 34 in the pin (see Fig. 6) and the top of the latch 20. To keep the parts in proper relationship, this spring 39 has a perforation into which projects a reduced portion 35^b (Fig. 6) from the pin 35. 30 This gripping action due to the spring 39 is released by depressing the aforesaid button 38, because then the toe 36^a (Figs. 3 and 6) lifts the pin 35 against the contrary action of the spring 39 and so releases the 35 wire-member 28 from the grip between the top of the eye 34 (Fig. 6) and the surface of the latch 20, whereupon the compression spring 32 (Figs. 1, 2 and 3) is free to assert itself, which it does by impelling said 40 wire-member 28 endwise.

The operation of this latch-releasing part of the stop is as follows: Suppose the brake is "off" as in Fig. 1 with the turntable rotating. When the sound-box has traveled 45 sufficiently far toward the center of the record for the end of the finger 12, swinging to the right in Fig. 1, to press against the projection 29 on the member 28, it will pull said member endwise and release the latch 50 55 60 65 20 from the brake-lever 17, whereupon the

spring 23 will pull the brake-shoe into contact with the turntable and stop its rotation. Further, it will be noted that by depressing the button 38, etc., the position of the aforesaid projection 29 can be adjusted so that 70 the operating finger 12 will contact with it to apply the brake at any desired point in the playing of the record, all of which will be made clear from the following connected description of the operation of the entire 75 device.

Assuming that the record is at rest with the brake on, as in Fig. 2, the operator will position the sound-box so that the stylus is located on the part of the record at which 80 the turntable is to be automatically stopped, for example, at the end of the record as shown in Fig. 2.

The operator will then depress the button 38, which will release the grip of the latch 85 20 on the rod 28, whereupon the spring 32 will impel the rod endwise until its projection 29 strikes against the operating-finger 12. The operator will then release the button, which will result in the rod 28 being 90 secured to the latch 20 with the projection 29 located in just the right position to be pressed by the operating finger when, in the subsequent playing of the record, the sound-box stylus has reached the selected stopping- 95 position on the record. Next, the operator will lift the sound-box and swing it and the tone-arm to the right, across the record and somewhat beyond until the operating finger, by pressing against the projection 26 100 on the brake-setting member 24, has forced the brake-shoe into "off" position, whereupon the latch 20 automatically latches it in said "off" position, and the turntable and record start and continue to rotate. The 105 operator will then lower the sound-box stylus into contact with the record which will then play until the predetermined end-part of the record is reached. At this moment, the end of the operating finger 12 will have 110 swung to the right (Fig. 2) sufficiently to press against the projection 29 and exert a pull on the latch 20, which, being withdrawn from its latching position, will release the brake-lever 17 so that the spring 115 23 pulls the brake-shoe against the turntable and stops its rotation.

It will be noted that latch 20 is slightly wider at 20^a than at 20^b. The purpose of this will appear from the following. The 120 projection 29 is positioned or set as described when the brake is "on" and therefore when the wider part 20^a of the latch is bearing against the brake-lever due to the spring 23 which when unopposed keeps said parts normally in contact. The projection 29 having been positioned as aforesaid, the brake is of course operated into its "off" or latched back position. This means that the 125 brake-lever now contacts with the narrower 130

part 20^b of the latch, which further means that the projection 29 is moved into a slightly different position from that in which it was originally "set" as described 5 from the selected, predetermined stopping groove on the record. And that slightly different position for the projection 29 is one that will be reached by the operating finger 12 slightly sooner than it otherwise 10 would have been. In short, the projection 29 will be reached by the finger somewhat before the stylus has reached the predetermined stopping-groove on the record, whereby a sufficient interval will be provided 15 wherein the rod 28 can be slightly moved endwise to pull back the latch 20 to release the brake, so that said braking actually occurs at substantially the moment the stylus reaches the predetermined groove.

20 Finally, it is not necessary to use the device all the time as an automatic brake. In other words, the described initial setting operation may be omitted, and the record started to rotate merely by swinging the tone-arm 25 sufficiently far to the right as described. To stop it at any subsequent time, it is merely necessary either to swing the tone-arm fully over to the left until the finger 12 strikes the projection 29 and pulls on the rod 28 to 30 unlatch and release the brake. Furthermore, the brake can be applied at any time 35 during the playing of the record, by momentarily depressing the button 38. This will result in the rod 28 adjusting itself end- 40 wise until its projection 29 strikes against the finger 12. After a few more turns of the record, the brake will be automatically applied, because during that slight interval the finger 12 will have traveled sufficiently 45 to pull the rod 28 to release the latch 20 from the brake-lever.

Of course, changes and modifications 45 might be made in the above that are nevertheless within the spirit of this inventive disclosure and these I mean to cover by the following claims under the doctrine of equivalents. Further, certain means might be used without the remainder or in connection with equivalent means.

50 Having thus described my invention, what I claim is:

1. In combination, a rotatable record support, a sound-box mounted to move across a record on said support, a member carrying 55 a brake normally tending to move into braking engagement with said record support, a latch to coöperate with said member and to hold said brake off, a pair of opposed members, one having a variable frictional connection to said latch and the other connected to the brake-carrying member, and a finger operatively connected to the movable sound-box and pivoted to swing to-and-fro in a plane beneath the record supporting 60 means, said finger acting during its move-

ment in one direction to trip the latch and cause the brake to engage the record supporting means and acting during its movement in the opposite direction to set the brake in its off position.

2. In combination, means for rotatably supporting a record, a sound-box mounted to move across said record supporting means, a brake-carrying member normally tending to move the brake into braking position relatively to the record supporting means, a latch for holding the brake in its off position, a pair of opposed members located in substantially the same plane and below the record supporting means, one of said members being adjustably connected to said latch and having means acting to shift its position in one direction relatively to the latch and the other member being connected to the brake-carrying member, and a finger operatively connected to the movably mounted sound-box and reciprocable in a plane beneath the record supporting means and between said opposed members, said finger acting during its movement in one direction upon one of said members to trip the latch and acting upon the other of said members during its movement in the opposite direction to set the brake in its off position.

3. In combination, means for rotatably supporting a record, a sound-box mounted to move across a record on said record supporting means, a brake-carrying member normally tending to move the brake into braking position relatively to the record supporting means, a latch coöoperative with the brake-carrying member to hold the brake in off position, a pair of opposed members, one having a manual releasable friction connection with said latch and the other connected to the brake-carrying member, said members having opposed up-turned abutments, and a finger operatively connected to the sound-box to swing to-and-fro between the abutments of said members, said finger acting during its movement in one direction upon one of said members to disengage the latch from the brake-carrying member, and acting during its movement in the opposite direction upon the other member to set the brake in its off position.

4. In combination, means for rotatably supporting a record, a sound-box mounted to swing across a record on said support, a brake-carrying member normally tending to move the brake into braking position, a latch coöoperative with the brake-carrying member to hold the brake in its off position, a pair of longitudinally movable members having opposed abutments, one of said members having means for variably connecting it to said latch and also means for shifting its positions relatively to the latch when said connecting means is released and the other

member being connected to the brake-carrying member, and a finger operatively connected to the sound-box and reciprocable between the opposed abutments of said longitudinally movable members, said finger acting during its movement in one direction to actuate one of said members to disengage the latch from the brake-carrying member and acting during its movement in the opposite direction to actuate the other of said members longitudinally to set the brake in its off position.

5. In an automatic stop, the combination of a sound-box; means for operatively supporting it to travel across a record; a stop member normally tending to terminate the travel of the sound-box; a controlling member for restraining said stop member and an operating device for said controlling member, comprising a swinging finger pivotally supported under the record, a link connection between said finger and the sound-box support to effect the swinging movement of the former during the travel of the sound-box, and means capable of being connected in different set relations with said controlling member and controlled by said finger for tripping said controlling member to bring said stop member into play when the sound-box reaches a selected position with relation to the record.

6. In an automatic stop, the combination of a sound-box; means for operatively supporting it to travel across a record; a stop member operable to terminate the travel of the sound-box; and an operating device for said stop member, comprising a swinging finger pivotally supported under the record, a connection between said finger and the sound-box support for swinging the former simultaneously with the sound-box, during the movement of said sound-box in either direction across the record, and means including a variable set part controlled by said finger for bringing said stop member into play when said sound-box reaches a selected position with relation to the record.

7. In an automatic stop, the combination of a sound-box; means for operatively supporting it to travel across a record; a stop member operable to terminate the travel of the sound-box; and an operating device for said stop member, comprising a swinging finger eccentrically pivoted under the record, a link connection between one end of said finger and the sound-box support, whereby when the sound-box is moved in either direction across the record the other end of said finger will be moved in the opposite direction through an increased distance, and means capable of being set in different positions and controlled by the said other end of said finger for bringing said stop member into play when said sound-box reaches a selected position with relation to the record.

8. In combination, an operatively supported sound-box, means for rotating a record, a brake normally tending into braking position, a latch for latching the brake in non-braking position, an operating part operatively connected to the sound-box and pivoted to swing to-and-fro in a plane beneath the record rotating means, a latch-releasing part comprising an abutment on an endwise movable member normally in the path of said operating part, means which tends to impel said member endwise to carry said abutment into contact with the operating part, releasable locking means between said member and the latch, manual means for momentarily releasing said lock, an abutment on another endwise movable member normally in the path of the operating part when moving in the opposite direction from that in which as aforesaid it strikes the first named or latch-releasing abutment, said other endwise movable member being operatively related to the brake to operate it into its "off" or latched position.

9. In combination with the traveling reproducer of a phonograph, a part traveling with said reproducer, a part to be operated by the traveling part when it has reached any chosen position, an adjustable connecting member between the traveling part and said operated part, spring actuated locking means between the operated part and the connecting member and operative automatically to lock said operated part, manual means for temporarily releasing said locking means, and means for impelling the connecting member, when released, toward the traveling part.

10. In an automatic stop, the combination of an operatively-supported sound-box; record-rotating means; a brake normally tending to assume a braking position; a latch for holding the brake in non-braking position, said latch being operative in a plane below the record rotating means; an operating part moving with the sound-box; an endwise movable, latch-releasing member having an abutment thereon normally in the path of the operating part, said latch releasing member operating in a plane below the record rotating means; and releasable locking means between said endwise-movable member and said latch permitting the endwise adjustment of the former relative to the latter, said locking means being located below the record rotating means and having an operating part extending outwardly beyond the edge of the record rotating means.

11. In a brake mechanism, the combination with a rotatable member, and a member adapted to travel thereacross; of a brake engageable with said rotating member; an operating part connected to move in unison with said traveling member; a spring-controlled part to bring the brake into action;

- and a spring actuated locking member for said spring-controlled part initially releasable to effect the initial setting of the spring-controlled part with relation to said operating part, and subsequently releasable to enable the operation of said spring-controlled part by said operating part. 5 70
12. In a brake mechanism, the combination, with a rotatable member, and a member adapted to travel thereacross; of a brake engageable with the rotating member; an operating part connected to move in unison with said traveling member; a controlling part for bringing the brake into action; and an automatically operative locking member for said controlling part initially releasable to effect the initial setting of the controlling part with relation to said operating part to be ultimately operated thereby when the traveling member reaches a predetermined position, and subsequently releasable at will to enable the substantially immediate operation of said controlling part by said operating part. 10 15 20 25 30 35 40 45 50 55 60 65 75 80 85 90 95 100 105 110 115 120 125 130
13. In a brake mechanism, the combination, with a rotatable member, and a member adapted to travel thereacross; of a brake member engageable with said rotating member; an operating member connected to move in unison with said traveling member; a spring impelled controlling part for bringing the brake into action; and an automatically operative locking member for said controlling part initially releasable to effect the initial setting of the controlling part with relation to said operating part, and subsequently releasable to enable the operative engagement of said controlling part by said operating part. 30 35 40 45 50 55 60 65 70 75 80 85 90 95 100 105 110 115 120 125 130
14. In a brake mechanism, the combination, with a rotatable member, and a member adapted to travel thereacross; of a brake member engageable with said rotating member; an operating member connected to move in unison with said traveling member; a controlling part for bringing the brake into action; a locking member for said controlling part, and a depressible releasing member for said locking member initially operable to effect the initial setting of the controlling part with relation to said operating part, and subsequently operable to enable the operative engagement of said controlling part by said operating part. 40 45 50 55 60 65 70 75 80 85 90 95 100 105 110 115 120 125 130
15. In a brake mechanism, the combination, with a rotatable member, and a member adapted to travel thereacross; of a brake member engageable with said rotating member; an operating member connected to move in unison with said traveling member; a controlling part for bringing the brake into action; a locking member for said controlling part and a depressible releasing member for said locking member mounted beneath said rotating member and having one end projected beyond the same and terminating in an operating portion, said locking member normally holding said controlling member against operation but releasable to permit the initial setting of said controlling member with relation to said operating part. 50 55 60 65 70 75 80 85 90 95 100 105 110 115 120 125 130
16. In a brake mechanism, the combination, with a rotatable member, and a member adapted to travel thereacross; of a brake engageable with the rotating member; a member for controlling the activity of said brake; a spring for actuating said controlling member; an operating part connected to move in unison with said traveling member and adapted to operatively engage said controlling member; and a manually operated locking member normally holding said controlling member against actuation, but releasable to effect the automatic initial setting of said controlling member by its spring with relation to said operating part. 75 80 85 90 95 100 105 110 115 120 125 130
17. In a brake mechanism, the combination, with a rotatable member, and a member adapted to travel thereacross; of a brake engageable with the rotating member; a member for controlling the activity of said brake; an operating part connected to move in unison with said traveling part and adapted to engage and operate said controlling member, said controlling member being adjustable for different settings relatively to said operating part; and a manually releasable spring actuated locking part normally holding said controlling member against change in its adjustment but releasable to permit the initial setting of said controlling member with relation to said operating part. 90 95 100 105 110 115 120 125 130
18. In a brake mechanism, the combination, with a rotatable member and a member adapted to travel thereacross; of a brake engageable with the rotating member; a member for controlling the activity of said brake disposed beneath said rotating member; an operating part disposed beneath said rotating part and connected to move in unison with said traveling part, said operating part adapted to engage and operate said controlling member; a locking member and a manually operated releasing member for said locking member pivotally mounted beneath said rotating part and having one end projecting beyond the same and terminating in an operating portion, said locking member normally holding said controlling member against operation but releasable to permit the initial setting of said controlling member with relation to said operating part. 110 115 120 125 130
19. In a brake mechanism, the combination, with a rotatable member, and a member adapted to travel in either direction thereacross; of a brake tending to engage the rotating member; a horizontally arranged operating part articulated to the 125 130

traveling part to move in unison with the same; means automatically actuated by said operating part, during the movement of the traveling member in one direction, for disengaging the brake, thereby to enable the movement of said rotating member; means for holding said brake in disengaged position during the movement of the traveling member in the other direction; and means 5 also actuated by said operating part and capable of being set in different relations with said holding means for automatically releasing said holding means when said traveling member reaches a selected point 10 in its second-named movement.

20. In a brake mechanism, the combination, with a rotatable member, means tending to rotate the same, and a member adapted to travel across said rotating member in either direction; of a brake tending to engage the rotating member; means for disengaging said brake operated automatically by the movement of said traveling member in one direction, thereby to enable the action 25 of said rotating means; means for holding the brake in disengaged position during the movement of said traveling member in the other direction; means for automatically releasing said holding means when said traveling member has reached a predetermined point 30 in its second-named movement; a

spring actuated friction lock for normally holding said releasing means in different set relations with said holding means; and a 35 depressible finger key for controlling said lock.

21. In a brake mechanism, the combination, with a rotatable member, means tending to rotate the same, and a member adapted to travel across said rotating member in either direction; of a brake tending to engage the rotating member; means for disengaging said brake operated automatically by the movement of said traveling member in one direction, thereby to enable the action 40 of said rotating means; means for holding the brake in disengaged position during the movement of said traveling member in the other direction; means operated automatically by the second-named movement of said traveling member for releasing said holding means when said traveling member has reached a predetermined point in such movement; and depressible manually-operated means movably related to said releasing means 45 for controlling the initial setting of the same, thereby to determine the position of such point.

In testimony whereof, I have signed my name to this specification this 22d day of 50 March, 1915.

RICHARD JAMES PRETTIE.
